CLAIM

The ornamental design for a combined speaker box with remote controller and charger, therefor as shown.

DESCRIPTION

FIG. 1 is a perspective view of a combined speaker box with remote control and charger showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of the speaker box with remote control of the combined speaker box with remote control and charger, shown separately from the charger to show aspects of the design that are not visible when combined;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and

FIG. 14 is a bottom plan view thereof.

FIG. 15 is a perspective view of the charger of the combined speaker box with remote control and charger, shown separately from the speaker box with remote control to show aspects of the design that are not visible when combined;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof; and,

FIG. 21 is a bottom plan view thereof.

(Continued)

The broken lines illustrating portions of the combined speaker box with remote control and charger form no part of the claimed design.
